UNITED STATES PATENT OFFICE.

PETER L. HEDBERG, OF CHICAGO, ILLINOIS.

WINDOW VENTILATOR AND SCREEN.

1,304,767.

Specification of Letters Patent.

Patented May 27, 1919.

Application filed February 17, 1919. Serial No. 277,675.

To all whom it may concern:

Be it known that I, PETER L. HEDBERG, a citizen of the United States, residing at the city of Chicago, county of Cook, and State of Illinois, have invented certain new and useful Improvements in Window Ventilators and Screens, of which the following is a specification.

This invention relates to improvements 10 in window ventilators and screens of a type wherein co-acting screen-carrying frames slidably engaging each other are employed in a window opening or similar locality for ventilation and for excluding dust, dirt and 15 insects, and it consists in certain peculiarities of the construction, novel arrangement and operation of the various parts thereof, as will be hereinafter more fully set forth and specifically claimed.

20 The principal object of the invention is to provide a ventilator and screen of simple construction, few parts, easy assemblage of said parts and readily adjustable to window openings of varying widths without 25 detaching any of its members, which can be located between the lower sash rail of the lower sash and window sill, or between the upper rail of the upper sash and the top of the window frame, or at said locations out- 30 wardly of the sashes, in such a manner as to permit of thorough ventilation, yet, so as to screen and purify the air. A further and important object is to provide the frames of the device with means for securely 35 yet detachably holding the screens of cloth or woven wire taut and in place thereon, to the end, that they can be readily removed for the purpose of washing or cleaning the same, and easily replaced. Still another 40 object is to provide means for the automatic adjustment, if desired, of the frames to the openings in which they may be located. Various other objects and advantages will be disclosed in the following description and 45 operation.

In the accompanying drawings, which serve to illustrate the invention—

Figure 1 is a plan or top edge view of the ventilator and screen showing its parts 50 partially extended;

Fig. 2 is a face view thereof with the parts in a similar position;

Fig. 3 is a cross sectional view taken on line 3—3 of Fig. 2 looking in the direction 55 indicated by the arrows;

Fig. 4 is a fragmental perspective view

of parts of one of the frames of the device showing them in the act of being assembled;

Fig. 5 is a top plan view illustrating a modification in the construction of the ventilator and screen;

Fig. 6 is a fragmental face view thereof;

Fig. 7 is a cross sectional view taken on line 7—7 of Fig. 6 looking in the direction indicated by the arrows; showing the application of the device to a window opening by placing it directly under the lower sash or outwardly thereof, a portion of said sash being shown in the dotted lines, and

Fig. 8 is a perspective view illustrating another modification in the construction of the ventilator and screen.

Like numerals of reference refer to corresponding parts throughout the different views of the drawings.

Referring now to Figs. 1 to 4 inclusive, the frames of the device are indicated as a whole by the reference numerals 10 and 11, which are located one on the other, and each of which is composed of an upper rail 80 or bar 12 and a lower rail or bar 13, which are connected together at their ends by means of end pieces 14, thus forming a rectangular frame with a rectangular opening. The ends of the upper and lower rails, as 85 well as the ends of the end pieces 14 are by preference formed with mortises 15 (see Fig. 4) to register with one another, so that said members may be secured together by means of glue or otherwise, in such a manner 90 as to present flush surfaces. Each of the rails or bars 12 and 13, as well as each of the end pieces 14, of each frame, is provided on its surface opposed to the other frame with a longitudinally extended ledge 16, 95 each of which is located inwardly from the outer edge of the rail or bar on which it is mounted, and by preference these ledges are made integral with said rails or bars. As is clearly shown in Fig. 4, each of the ledges 16 has in its outer surface a groove 17, 100 and each of the rails 12, as well as each of the end pieces 14 has on its surface adjacent to its ledge a kerf or depression 18, which, as shown, are located near the perimeters 105 of the frames. When the members of the frames are assembled, it will be understood that the ledges 16 of said members will practically form a continuous ledge as is clearly shown in Fig. 2 of the drawings.

On the surface of each of the adjacent end pieces of the frames 11 and 12 is mounted

a cleat 19, which has a rabbet 20 at each of its ends to receive tenons 21, with which each of the top and bottom rails of each frame is provided on its inner surface. Located on the face of each of the ledges 16, when the parts are assembled as shown in Figs. 2 and 3, is a screen 22 of cloth or woven wire, the edges of which overhang the outer edges of the cleats 16, which edges are forced 10 into and held in the grooves 17 of the ledges by means of detachable clamping cleats 23, each of which has on its inner surface a rib 24 to extend into said grooves. By this arrangement, it is apparent that the screens 15 22 will be held in a taut condition on the faces of the ledges 16 and over the openings in the frames in such a manner as to prevent their removal or dislocation, except by detaching the clamping cleats 23, each of which 20 is provided with one or more pivoted catches 25 to engage the kerfs or depressions 18 in the rails 12 and 13 and end pieces 14. Each of the catches 25 may have on its outer surface a lip 26 by means of which the catch 25 can be readily turned on its pivot so as to cause them to engage the kerfs or be disengaged therefrom. It will be understood that the adjacent end portions of the frames 10 and 11 overlap each other, as shown in Figs. 30 1 and 2, thus providing a space between the adjacent end pieces 16 and 19 of said frames, which end pieces may be united by a contracting spring 27, having its ends connected to the inner surfaces of said end pieces, 35 which spring will act to draw the said end pieces toward each other, thus automatically extending the frames 10 and 11 from their retracted or telescoped positions. This spring can be detached at either of its ends 40 or removed when it is desired to fold the frames together for shipment.

In Figs. 5 to 7 inclusive, is shown a modification which consists in employing a pair of frames and screens of the same construction as illustrated in Figs. 1 to 4 inclusive and above described, except that the clamping cleat 23 on the upper rail of one of the frames (see Fig. 6) is shorter than the corresponding cleat on the corresponding frame 50 of the other construction (see Fig. 2) in order to allow the clamping cleat 23 on the inner end of said frame to extend at its upper end so as to be flush with the upper surfaces of the upper rails of the frames. 55 In this modified construction a plate or flat strip 28 is secured to the upper surface of the upper rail of one of the frames, and said plate or strip has therein a longitudinal recess or slot 29 to receive a tongue 30 extending from another flat plate or strip 31 secured to the upper surface of the upper rail of the other frame. By this arrangement, it is obvious that when the frames are moved toward or from each other the tongue 30 will 60 slide in the recess or slot 29, thus permitting 65

the frames to be adjusted to any suitable width. By the use of the flat strips or plates 28 and 31, it is apparent that the device can be located in the window opening outwardly of the lower sash, as shown at 32 by dotted lines in Fig. 7 of the drawings, or the device may be located directly under the lower sash, as shown at 33 by dotted lines in said figure of the drawings. This arrangement, when the device is located as shown at 32 70 with respect to the sash, will permit the size of the opening in the frames to be regulated, and it is evident that the sash can be raised or lowered without removing the ventilator and screen, which, of course, will be properly supported at its ends to the jambs of the window sill. By extending the vertical clamping cleat 23 upwardly at the inner end of one of the frames, as shown in Fig. 6, it is apparent that if any dust or soot should 75 enter between the plates 28 and 31 on the upper surface of the horizontal cleat 23 on the top of frame 10, it will be excluded from the room by reason of the closure provided by the clamping cleat 23 at the inner end of 80 said frame. In order to enable the cleat 23 on the upper rail of the frame 10 to be removed without interference by the plates 28 and 31 the said cleat 23 is made narrower than in the other or first described construction, and 85 the kerf 18 in said upper rail is located farther inwardly from its edge so as to permit said cleat after being released by the catch 25 to be moved outwardly far enough to release the rib 24 on said cleat from the 90 groove 17, thereby freeing the edge of the screen held by said cleat.

In Fig. 8 is shown another modification which is of exactly the same construction as illustrated in Figs. 5 to 7 inclusive and 105 above described, except that a flat plate 34 mounted on the upper rail of the frame 12, and having an L-shaped recess 35 at one of its ends is employed to receive a portion of another flat plate 36, mounted on the upper 110 surface of the upper rail of frame 11 of the device.

Having thus fully described my invention what I claim as new and desire to secure by Letters Patent is—

1. In a device of the class described, the combination with a frame having on one of its faces a ledge corresponding in shape with said frame but of less size and having a longitudinal groove in each of its outer walls, of a screen of flexible material located on the face of the ledge and overhanging its edges, and a clamping-cleat located at each outer edge of said ledge and each having a rib to force and hold the edges of the 120 screen in said grooves.

2. In a device of the class described, the combination with a frame having on one of its faces a ledge corresponding in shape to said frame but of less size and having 125

grooves in its perimeter, the frame also having on its said face a kerf or depression near each of its outer edges, of a screen of flexible material located on the face of the 5 ledge and overhanging its edges, a detachable clamping-cleat located at each outer edge of said ledge and each having a rib to force and hold the edges of the screen in said grooves, and a catch on each cleat to 10 engage said depressions.

3. In a device of the class described, the combination with a pair of superimposed and slidably engaging frames, each having on its opposed face a ledge corresponding in 15 shape with the frame but of less size and each ledge having a longitudinal groove in each of its outer walls, of a screen of flexible material located on the face of each ledge and overhanging its edges, and a clamping- 20 cleat located at each outer edge of each ledge and each cleat having a rib to force and hold the edges of the screen in said grooves.

4. In a device of the class described, the combination with a pair of superimposed and slidably engaging frames, each having on its opposed face a ledge corresponding in shape with the frame but of less size and each ledge having a longitudinal groove in each 30 of its outer walls, of a screen of flexible material located on the face of each ledge and overhanging its edges, a spring connecting the adjacent ends of said frames, and a clamping-cleat located at each outer edge of 35 each ledge and each cleat having a rib to force and hold the edges of the screen in said grooves.

5. In a device of the class described, the combination with a pair of superimposed and slidably engaging frames, each having on its opposed face a ledge corresponding in shape with the frame but of less size and each ledge having a longitudinal groove in each of its outer walls, each frame also having on its opposed face a kerf or depression near each of its outer edges, of a screen of flexible material located on the face of each ledge and overhanging its edges, and a detachable clamping-cleat located at each outer 50 edge of each ledge and each cleat having a rib to force and hold the edges of the screen in said grooves, and a catch on each cleat to engage said depressions.

6. In a device of the class described, the combination with a pair of superimposed frames each having on its opposed face a ledge corresponding in shape with the frame but of less size and each ledge having a longitudinal groove in each of its outer walls, 60 each of said frames also having on its opposed inner longitudinal edges a tenon and on the inner face of their adjacent ends a

transverse cleat each having a rabbet in each of its ends to receive said tenons, of a screen of flexible material located on the face of each ledge and overhanging its edges, and a clamping-cleat located at each outer edge of each ledge and each cleat having a rib to force and hold the edges of the screen in 70 said grooves.

7. In a device of the class described, the combination with a pair of superimposed frames each having on its opposed face a ledge corresponding in shape with the frame but of less size and each ledge having a longitudinal groove in each of its outer walls, each of said frames also having on its opposed inner longitudinal edges a tenon and on the inner face of their adjacent ends a transverse cleat each having a rabbet in each 75 of its ends to receive said tenons, each of said frames further having on its opposed face a kerf or depression near each of its outer edges, of a screen of flexible material located on the face of each ledge and overhanging its edges, and a detachable clamping-cleat located at each outer edge of each ledge and each cleat having a rib to force and hold the edges of the screen in 80 said grooves, and a catch on each cleat to engage 85 said depressions.

8. In a device of the class described, the combination with a pair of superimposed rectangular frames each having on its opposed face a ledge corresponding in shape with the frame but of less size, and each ledge having a longitudinal groove in each of its outer walls, each of said frames also having on its opposed inner longitudinal edges a tenon and on the inner face of their 95 adjacent ends a transverse cleat each having at each of its ends a rabbet to receive said tenons, of a flat strip longitudinally mounted on the upper rail of one of said frames and having a longitudinally extended cut-out in its end adjacent the other frame, another flat strip similarly mounted on the upper rail of the last named frame and having a portion to fit in said cut-out, each of 100 said frames further having on its opposed face a kerf or depression near each of its outer edges, a screen of flexible material located on the face of each ledge and overhanging its edges, a detachable clamping-cleat located at each outer edge of each ledge 110 and each of said cleats having a rib to force and hold the edges of the screen in said grooves, the vertical cleat at the inner end of each frame extended upwardly and terminating flush with the upper surface of the 120 rails at the top of the frames, and a catch on each clamping-cleat to engage said depressions.

PETER L. HEDBERG.
